THE BOSTONIAN

William H. James Inventor

By Joseph Miller

UNITED STATES PATENT OFFICE.

WILLIAM A. JAMES, OF PROVIDENCE, RHODE ISLAND.

DIESTOCK.

Application filed May 5, 1922. Serial No. 558,566.

To all whom it may concern:

Be it known that I, WILLIAM A. JAMES, a citizen of the United States, residing at Providence, in the county of Providence and 5 State of Rhode Island, have invented new and useful Improvements in Diestocks, of which the following is a specification:

This invention relates to certain new and useful improvements in die stocks; the 10 primary object thereof is to provide a construction of die stocks in which the manufacture is greatly facilitated, and more specifically by permitting a cutting tool to be moved or run into the yoke in order to 15 form the two guide ways for the die and to properly finish such guide ways.

A further object of the invention is to provide a die stock which is so constructed as to prevent the die from being placed 20 wrong-side up, as in the usual yoke, which latter has the guide ways formed in its arms.

A still further object of the invention is to provide a die stock which has improved means of simple and positive character for 25 holding the dies in the stock.

The invention still further aims to provide a die stock which is of simple and durable construction, and which also can be economically and expeditiously produced.

30 Still further and other object will be later set forth and manifested in the course of the following description.

In the drawings:

Figure 1 is a plan view of a die stock 35 embodying in the invention, the handles being shown in fragment;

Figure 2 is a front edge elevation;

Figure 3 is a section on line 3—3 of Figure 1, with the dies omitted to clearly show 40 the guide ways;

Figure 4 is a top plan view of a modified form of the invention, parts being shown in fragment, and

Figure 5 is a front edge elevation of Figure 4.

In proceeding in accordance with the present invention the die stock has a body composed of a yoke 1 and the usual handles 2. The yoke has parallel arms 3 and are connected at their outer ends by a bridge 4, which latter is disposed slightly below the entrance into the yoke for the dies D or below the plane of the yoke. By virtue of this disposition of the bridge 4, it will be seen that cutting or other tools employed in forming and finishing the guideways 5

may be moved or run into the space between the arms 3 so as to conveniently and expeditiously form and finish the guideways. The stock is further formed with 60 a threaded socket 6 in which a screw device 7 is mounted, the latter having an end 8 which impinges against the innermost die D to hold same in position. In order to secure the dies against movement out of the yoke, 65 turn buttons 9 are employed which have threaded shanks that are received in threaded sockets 10 provided therefor in the parallel arms 3 of the yoke. As depicted in Figures 1 and 2 of the drawings the heads of the turn 70 buttons overlap the ends of the outermost die D, and are impinged thereagainst, so that it will be readily seen the dies are positively held within the yoke.

By referring to Figures 2 and 3 of the 75 drawings it will be seen that the guideways 5 are located closer to the bottoms of the arms 3 than to the tops thereof so that it is impossible to place the dies wrong side up in the yoke, and the latter are thus assured of 80 being properly positioned at all times when in operative engagement with the yoke.

In Figures 4 and 5 of the drawings a modified form of the invention is illustrated and wherein a different type of means is 85 illustrated for locking or latching the dies in the yoke. In this form of the invention a pivoted bridge 20 is employed which is formed to engage throughout the front side of the foremost die D. The bridge is secured in place by screws 21 which have operating heads 22, one end of the bridge 20 having a U-shaped slot 23 which engages over the adjacent screw 21, so that it is merely necessary to loosen one of the screws 95 in order to swing or move the bridge 20 upwardly for the purpose of allowing the dies to be moved out of the yoke.

In the form of the invention shown in Figures 1 to 3 the heads of the turn buttons are flattened or cut-away as depicted at 24, which is for the purpose of causing said cut-away edges, upon partial turning of the turn-buttons 9 to lie in register with the inner side faces of the arms 3 of the yoke, 100 whereby upon such registry being effected, the dies may be slid out of the guide-ways and new ones substituted. The turn buttons are then merely given a partial rotation to cause the uncut-away parts thereof to partly 110 overlie the space between the arms of the yoke, as depicted in Figures 1 and 2, thus

locking or latching the dies in the yoke. It will thus be seen that complete removal of the turn buttons is not necessary, and in fact but partial rotation of each is required in 5 order to both latch and unlatch the dies.

Having thus described my invention, what I claim as new and desire to secure by Letters Patent is:—

1. A die stock including a yoke having 10 parallel arms, a rigid bridge connecting the outer ends of the arms and disposed slightly below the plane of the lower sides of the arms, guide-ways formed on the inner side faces of the arms and located to one side of 15 the vertical center of the arms so as to prevent misplacement of the dies in the yoke, and turn-buttons having threaded shanks threaded into the outer ends of the arms, the turn buttons having cut-outs on their 20 heads, which cut-outs upon rotation of the turn buttons register with the inner side of the yoke to allow the dies to be slid out of the latter, and upon further rotation have the uncut-away parts of their heads in overlapping relation to the inner side faces of 25 the arms of the yoke to latch the dies in the latter.

2. A die stock including a yoke having 30 parallel arms, a rigid bridge connecting the outer ends of the arms and disposed slightly below the plane of the lower sides of the arms, guide-ways formed on the inner side faces of the arms and located to one side of

the vertical center of the arms so as to prevent misplacement of the dies in the yoke, 35 and turn-buttons having threaded shanks threaded into the outer ends of the arms.

3. In a die stock, a yoke having guide ways, said guide ways being located so as to lie closer to one side of the longitudinal axis 40 of the guide ways than to the opposite side of such axis, so as to prevent misplacement of the dies in the yoke, and means to hold the dies in the yoke.

4. A die stock including a yoke having 45 parallel arms, a rigid bridge connecting the free outer ends of the arms and having its upper face disposed slightly below the plane of the lower side faces of the arms, and guide-ways formed on the inner side faces 50 of the arms.

5. In a die stock, a yoke having parallel arms, guideways on the inner side faces of the arms formed to receive the dies, and turnable means threaded into the outer end 55 of each of the arms and formed to latch the dies in the yoke in one position and in a second position to allow the dies to be removed from the yoke.

In testimony whereof I have signed my 60 name to this specification in the presence of two subscribing witnesses.

WILLIAM A. JAMES.
